United States Patent Office

Des. 203,220
Patented Dec. 14, 1965

203,220

DOOR HANDLE

Leo J. Maffei, New Britain, Conn., assignor to Emhart Corporation, Bloomfield, Conn., a corporation of Connecticut

Filed Apr. 15, 1965, Ser. No. 84,804

Term of patent 14 years

(Cl. D50—3)

FIG. 1 is a front elevational view illustrating the door handle embodying my new design.

FIG. 2 is a side elevational view of said door handle, the opposite side being a mirror image of that shown.

FIG. 3 is an elevational view illustrating the left-hand end of said door handle as viewed in FIG. 2.

FIG. 4 is a similar view illustrating the opposite end of the door handle.

FIG. 5 is a rear elevational view of said door handle.

I claim:

The ornamental design for a door handle, substantially as shown.
